Primary Examiner — Stacia Cadmus*(74) Attorney, Agent, or Firm* — Westerman, Hattori, Daniels & Adrian, LLP(57) **CLAIM**

The ornamental design for a wheel for automobiles, as shown and described.

DESCRIPTION

FIG. 1 is a front view of a wheel for automobiles showing my new design; and,

FIG. 2 is a front perspective view of a wheel for automobiles as seen from the right side.

The broken line showing of the valve stem hole, the bolt holes and the rear portion of the rim is included for the purpose of illustrating environment and forms no part of the claimed design.

1 Claim, 2 Drawing Sheets**FIG.1**

FIG.2
